UNITED STATES PATENT OFFICE.

WILMER W. SALMON AND FRANK L. DODGSON, OF ROCHESTER, NEW YORK, ASSIGNORS
TO GENERAL RAILWAY SIGNAL COMPANY, OF GATES, NEW YORK, A CORPORATION
OF NEW YORK.

RECORDING DEVICE.

1,162,656.

Specification of Letters Patent.

Patented Nov. 30, 1915.

Application filed September 28, 1912. Serial No. 722,812.

To all whom it may concern:

Be it known that we, WILMER W. SALMON and FRANK L. DODGSON, citizens of the United States, and residents of the city of 5 Rochester, in the county of Monroe and State of New York, have invented a new and useful Recording Device, of which the following is a specification.

This invention relates to railway signal- 10 ing.

Modern systems of fixed signaling are often criticized, because they almost invariably fail to provide a means, whereby a train improperly entering a signal section 15 is stopped irrespective of any voluntary action by the engine runner.

The primary object of this invention is to provide a means, whereby a record will be automatically made of the passage of a 20 train into an occupied signal section, of such a character, that at any future time it may readily be determined at what particular time the signal section was thus entered.

The advantage of the invention resides in 25 the fact, that engine runners knowing a permanent and indisputable record will be made if they allow their train to enter an occupied signal section, will be extremely careful not to do so. This extreme precau- 30 tion on the part of engine runners will undoubtedly result in very materially decreasing the number of collisions now due to the entrance to an occupied section of a second train.

35 Other objects and advantages will appear as the description of the invention progresses, and the novel features of the invention will be particularly pointed out in the appended claims.

40 In describing the invention in detail, reference is had to the accompanying drawings, wherein we have illustrated a preferred physical embodiment of our invention, and wherein like characters of reference designate 45 corresponding parts throughout the several views, and in which—

Figure 1 is a schematic illustration of a preferred physical embodiment of our invention; Fig. 2, is a schematic illustration of 50 another embodiment; Fig. 3, is a schematic illustration of a modification of the embodiment of Fig. 1; Fig. 4, is a schematic illustration of a modification of the embodiment of Fig. 2.

55 Referring to Fig. 1, 1 and 2 designate the

two rails of a railway track having the ordinary and well known insulating joints, as 3, inserted in both rails at intervals, forming what is known as the ordinary and well known block, the entrance to which, by 60 trains, is governed by the fixed signal 4. The insulating joint 5, inserted in the rail 2, divides the block into two track circuit sections, designated by A and A¹. A difference of potential is created between the rails 65 of section A by means of the source of current 6, and a difference of potential is created between the rails of section A¹ by means of the source of current 7. Section A¹ controls the ordinary and well known track 70 relay 8, the terminals of which, 9 and 10, are connected to each track rail, 1 and 2. The armature 11 of relay 8 is included in the circuit of relay 12, which circuit also includes the rail 2 between the insulating 75 joints 5 and 3 at the right hand end of section A, the battery 6, the rail 1 between insulating joints 3 in rail 1 at either end of the block, the lead 13 which also serves to connect relay 8 with rail 1, the conductor 14 80 and conductor 15. This arrangement as is well understood by those skilled in the art, causes a deenergization of both relays 8 and 12 by the presence of a train upon section A¹ and a deenergization of relay 12 only by the 85 presence of a train upon section A.

The armature 16 of relay 12 controls the fixed signal 4, the circuit of which is as follows: one terminal of battery 17, conductor 18, armature 16, conductor 19, mechanism of 90 fixed signal 4, conductor 20 and conductor 21 to the other terminal of the source of current 17. As is obvious and is well understood by those skilled in the art, the fixed signal 4 is moved to and held in the full clear position as shown, when the armature 16 is in its upper position as shown. When a train passes the insulating joint 3 at the left hand end of section A¹, the relay 8 is shunted, consequently the armature 11 drops, thus breaking the circuit of relay 12 and allowing the armature 16 to fall, thereby breaking the circuit of the fixed signal 4 and allowing it to fall to the danger position. When the train afterward entirely passes the insulating 100 joint 5 the relay 12 still remains deenergized by reason of the fact that the wheels and axle of the train shunt from relay 12 the current which normally flows thereto from battery 6, so that the relay armature remains 105 110

in the lower position all of the time while any part of a train is upon the rails of the track between the insulating joints at either end of section A, and, consequently the fixed signal 4 remains in the danger position. When signal 4 moves to the danger position it causes circuit controller arm 21 to move in contact with the contact 22. If another train enters section A¹ while a preceding train is upon the section A, the fixed signal 4 necessarily being under such conditions in danger position and the circuit controller arm 21 making contact with contact 22, then as following train will deenergize relay 8, its armature 23 will fall and in falling will make contact with member 24, thus completing the following circuit; one terminal of the source of current 17, conductor 18, armature 16, conductors 25 and 26, contact 22, circuit controller arm 21, conductor 27, armature 23, member 24, conductors 28 and 29, recording device 30, and conductors 31 and 21 to the other terminal of the source of current 17. Current flowing in the above traced path will cause an actuation of recording device 30 which may be of any well known type, by which a record of the exact time at which it was actuated will be permanently made. Regardless of the exact type of recording mechanism 30 that may be used there will in all cases be a means such as member 32 operated simultaneously or by the mechanism of recording device 30, pivoted at 33 for the purpose of giving an indication, external to recording mechanism 30, that the same has been actuated. In the present case the pivoted member 32 is connected with a link 34, which at its upper end carries a catch 35 which normally engages with an arm 36 attached to a disk 37 which carries a weight 38, which normally lies in the upper position as shown. When the pivoted member 32 is actuated by an electrical energization of recording device 30, the link 34 will be drawn downwardly and the projection 39 rigidly attached to said link will contact with the fixed projection 40 attached to the side of recording device 30, and cause link 34 to be moved outwardly, so that catch 35 disengages arm 36 and allows disk 37 to be moved to another position by virtue of weight 38 tending to lower the center of gravity of the disk 37. The link 34 and catch 35 are normally held in engagement with arm 36 by means of spring 41 which exerts a constant tension upon link 34.

In practice the recording device 30 would ordinarily be placed in the same case with the mechanism for operating the fixed signal 4, so that by means of the external indicating mechanism above described it may immediately be determined whether or not any train has improperly passed fixed signal 4, since the last inspection, by merely opening 60 the door of the case inclosing the mechanism

for controlling fixed signal 4, and glancing at the recording mechanism 30. If the recording mechanism 30 has been actuated, it will be shown by the position of disk 37 and an internal inspection of recording device 30 will show the exact time or times at which it was actuated, which will be noted, then the disk 37 will be manually returned to its normal position, as shown in Fig. 1.

The armature 23 of relay 8 is so constructed and pivoted that when it falls it will first contact with member 24 and then pass beyond it out of contact with it and the member 24 has an insulating member 42 attached to its underside so that when armature 23 rises it will not form an electrical contact. This construction and mode of operation are necessary in order to prevent an actuation of the recording mechanism 30 by a train which accepts a clear signal or by a train which has accepted signal 4 and passed into section A and then passes out of section A at the right hand end. If armature 23 remained in contact with member 24 during all the time the relay 8 was deenergized, the recording mechanism 30 would be actuated every time a train entered upon section A¹ and passed onto section A, because the entrance of the train upon A¹ would cause signal 4 to move to the danger position and at the instant of its passage onto section A, the relay 8 being deenergized, and signal 4 in the danger position and relay 12 deenergized, a circuit would be formed through the recording device. The contact of armature 23 with member 24 when it moved upwardly when a train passed out of section A at the right hand end would also cause an actuation of recording mechanism 30 if the insulating member 42 were not attached to the underside of member 24, because when a train passes from the right hand end of section A the signal 4 is in the danger position, the circuit controller arm is in contact with contact 22 and the armature 16 is making contact with conductor 25, so that all parts are in condition to complete a circuit through the recording device if armature 23 makes contact with member 24.

Although ordinarily a fixed signal when in the danger position should not be passed by a train, there are times especially in the case of automatic electric block signaling where under proper precautions it is proper to pass a signal when in the danger position. Some means must, therefore, be provided, whereby an engine runner may indicate that although the signal was in the danger position, he passed it knowingly. Such a means in applicants' invention is provided in the push button 43. If the fixed signal 4 is in the danger position, so that a record will be made if a train passes into section A¹, then if the engine runner actually desires to enter the section, he may assume the

responsibility, but indicate his knowledge by depressing the push button 43. The depression of push button 43 connects conductors 44 and 45 so that a circuit is formed 5 as follows: terminal of the source of current 17, conductor 18, armature 16, conductors 25 and 44, push button 43, conductors 45 and 29, recording device 30, and conductors 31 and 21 to the other terminal of the source of current 17. Current flowing in the above traced path will cause an actuation of recording device 30, so that the exact time 10 will be recorded at which push button 43 was depressed. The engine runner will then 15 immediately cause his train to move upon the section A¹, which will cause another actuation of recording device 30 and an exact indication of the time at which the train entered the section. A later inspection of 20 the record made by device 30 will then show, that the signal 4 was passed by an engine runner with full knowledge of the condition and with an entire assumption of the responsibilities by him.

25 All parts in Fig. 2 similar to parts shown in Fig. 1 are designated by the same numerals.

In the modification shown by Fig. 2 the entrance of a train upon section A¹ will 30 cause signal 4 to move to the danger position, just as in the embodiment shown by Fig. 1 and a further movement of the train onto section A will result in the energization of stick relay 46. This is accomplished 35 as follows: Upon the entrance of the train to section A¹ the relay 8 is deenergized in the well known manner, which causes a deenergization of relay 12 thus allowing armature 16 to fall, thus breaking the circuit 40 for signal 4 and allowing it to fall to the danger position, causing circuit controller arm 21 to make contact with contact 22, and as armature 47 is allowed to fall by the deenergization of relay 12, as soon as the train 45 has passed entirely from section A¹ to section A, the following circuit will be formed: one terminal of the source of current 17, conductors 48 and 49, circuit controller arm 21, contact 22, conductor 50, armature 51, 50 conductor 52, armature 47, conductor 53, stick relay 46 and conductors 54, 55 and 56 to the other terminal of the source of current 17. It will be noted that the above traced circuit cannot be formed until all of 55 the train has passed beyond section A¹ for until such is the case, the armature 51 will not be in the upper position, but when the armature 51 is in the upper position and the circuit above traced is completed, the 60 current flowing therein will cause the stick relay 46 to be energized, thereby causing armatures 57 and 58 to be raised to the upper position. After relay 46 has been energized by the circuit heretofore described, it 65 is kept in the energized condition by reason

of a current flowing in the following circuit: one terminal of the source of current 17, conductors 48, 60 and 69, armature 57, conductor 70, armature 47, conductor 53, stick relay 46 and conductors 54, 55 and 56 70 to the other terminal of the source of current 17. This circuit remains completed as long as armature 47 is in the lower position which continues as long as relay 12 is deenergized, and as has heretofore been pointed out relay 12 remains deenergized as long 75 as a train remains upon the rails of section A, so that the relay 46 will remain energized until the train which has accepted signal 4 has passed beyond the insulating joints at the right of section A. When a train is upon section A and the armatures 57 and 58 are in the upper position due to an energization of relay 46, then the entrance of a second train upon the section 80 A¹ will cause the relay 8 to be deenergized, thereby causing armature 59 to fall and completing a circuit as follows: one terminal of the source of current 17, conductors 48, 60 and 61, recording device 30, 85 conductor 62, armature 59, conductors 63 and 64, armature 58, and conductors 65, 55, and 56 to the other terminal of the source of current. Current flowing in the above traced path will cause an energization of recording 90 device 30, recording the exact time of actuation and a release of indicating member 37. If an engine runner finds signal 4 in the danger position, but still wishes to enter the section A¹, he may indicate his assumption 95 of responsibility by depressing the push button 43, whereupon a circuit will be formed as follows: one terminal of the source of current 17, conductors 48, 60 and 61, recording device 30, conductors 66 and 100 67, push button 43, conductors 68 and 64, armature 58 and conductors 65, 55 and 56 to the other terminal of the source of current 17. The depression of the push button 43 by the engine runner and his subsequent 105 entrance into the section A¹ indicate the same facts that were discussed in connection 110 with the description of the embodiment shown by Fig. 1.

Fig. 3 illustrates a modification of the embodiment of applicants' invention shown by Fig. 1. In this figure the invention is shown as embodied in an apparatus not including the circuit controller 21 of Fig. 1. All of the parts shown in this figure similar to 115 those shown in Fig. 1 have been designated by like characters of reference. The energizing circuit for recording device 30 is as follows: One terminal of the source of current 17, conductor 18, armature 16, conductors 25 and 27, armature 23, member 24, conductors 28 and 29, recording device 30, and conductor 31 to the other terminal of the source of current 17. The operation 120 and circuits of the remainder of the figure 125 130

are the same as those shown and described in connection with Fig. 1 and further explanation is therefore unnecessary.

The device shown by Fig. 4 is a modification of the embodiment illustrated by Fig. 2 and differs from it in exactly the same way that the embodiment shown by Fig. 3 differs from the embodiment shown in Fig. 1. All parts similar to those shown in Fig. 2 are similarly numbered. The energizing circuit for the recording device is as follows: one terminal of the source of current 17, conductors 71, 72 and 73, recording device 30, conductors 66 and 62, 15 armature 59, conductors 63 and 64, armature 58, and conductors 55 and 65, to the other terminal of the source of current. The pick up circuit for relay 46, is as follows: one terminal of the source of current 17, conductors 71, 72 and 74, armature 51, conductor 52, armature 16, conductor 53, stick relay 46, and conductors 54 and 55 to the other terminal of the source of current. The remaining circuits together with the 25 devices associated therewith are the same as the embodiment shown by Fig. 2 and operate similarly so that further explanation is not required.

Applicants have not herein described any 30 particular form of mechanism for that device designated by numeral 30, because the form of mechanism designated by 30 is immaterial to the substance of applicants' invention because applicants' invention 35 templates the use of any form of recording or registering mechanism which upon actuation will make or exhibit a permanent record of the fact and the exact time of its actuation, and applicants wish it to be distinctly understood that they consider any 40 such form of mechanism to be designated and indicated by means of numeral 30.

Although applicants have herein shown and described their novel recording device 45 in connection with an automatically operated signal, it is to be clearly understood that its use is not so limited. The essential feature of the applicants' invention is such that it may be used as well in connection with 50 the manually operated as with the automatically operated signal, in fact it is necessary merely to employ track circuit sections and relays controlled thereby, arranged according to the principle of applicants' invention, in order to enable applicants' recording device to perform its function irrespective of any signal.

Although applicants have particularly described the construction of preferred physical embodiments of their invention, and have explained the operation and principle thereof, nevertheless, they desire to have it understood that the forms selected are merely illustrative, but do not exhaust the

possible physical embodiments of their idea 65 of means underlying their invention.

What we claim as new and desire to secure by Letters Patent of the United States, is:

1. A block; a signal governing entrance to the block; a recording device adapted 70 to be electrically actuated; a normally open circuit including a source of electro-motive force, a circuit controller operated by the signal and the recording device; means governed by the presence of one train in the 75 block for causing the signal to operate the circuit controller and means governed by the entrance of another train thereto for completing the closure of said normally open circuit thus actuating the recording 80 device.

2. A block; a signal governing entrance to the block; a recording device adapted to be electrically actuated; a normally open circuit including a source of electro-motive 85 force, a circuit controller operated by the signal and the recording device; means governed by the presence of one train in the block for causing the signal to operate the circuit controller; means governed by the 90 entrance of another train thereto for completing the closure of said normally open circuit thus actuating the recording device; and an indicator operated by the recording 95 device.

3. A block; a recording device adapted to be electrically actuated; a normally open circuit including a source of electro-motive force and the recording device; means governed by the presence of one train in the 100 block and the entrance of another train thereto for closing said normally open circuit and actuating the recording device; and means for manually closing said normally open circuit and actuating the recording 105 device when a train is in the block.

4. A block; a signal governing entrance to the block; a recording device adapted to be electrically actuated; a normally open circuit including a source of electro-motive 110 force and the recording device; a plurality of track circuit sections within the block; a translating device controlled by each track circuit section; breaks in the normally open circuit controlled by the translating devices; 115 all so arranged that a deenergization of the translating device controlled by the track circuit section adjacent the signal, when another translating device controlled by another of the plurality of track circuit sections is deenergized causes the normally open circuit 120 to be closed and the recording device to be actuated.

5. A block; a signal governing entrance to the block; a circuit controller operated by the signal; a recording device adapted to be electrically actuated; a normally open circuit including a source of electro-motive 125

- force and the recording device; a plurality of track circuit sections within the block; a translating device controlled by each track circuit section; breaks in the normally open circuit controlled by the translating devices; all so arranged that a deenergization of the translating device controlled by the track circuit section adjacent the signal, when another translating device 5 controlled by another of the plurality of track circuit sections is deenergized and the circuit controller operated by the signal is in closed position causes the normally open circuit to be closed and the recording device 10 to be actuated; and an indicator operated by the recording device.
6. A block; a signal governing entrance to the block; a circuit controller operated by the signal; a recording device adapted to 15 be electrically actuated; a normally open circuit including a source of electro-motive force and the recording device; a plurality of track circuit sections within the block; a translating device controlled by each track 20 circuit section; breaks in the normally open circuit controlled by the translating devices; all so arranged that a deenergization of the translating device controlled by the track circuit section adjacent the signal, when another translating device 25 controlled by another of the plurality of track circuit sections is deenergized and the circuit controller operated by the signal is in closed position causes the normally open circuit to be closed and the recording device to be actuated; and means for manually operating the recording device when said another translating device has closed a break in the 30 normally open circuit.
7. A recording device; adapted to be electrically actuated; a block; one track circuit section within the block; a second track circuit section within the block; a normally open circuit containing a source of electro- 35 motive force and said recording device; means controlled by said track circuit sections, whereby an occupation of said first track circuit section by a train, then the 40 passage of said train entirely into the second track circuit section, and the subsequent oc-

cupation of said first track circuit section by a train, while the first mentioned train occupies the second section, closes said normally open circuit and actuates the recording device; another normally open circuit 55 containing said recording device, a source of electro-motive force, and a manually operable circuit controller.

8. A first normally closed track circuit section; a second abutting normally closed 60 track circuit section; translating devices including movable members governed by the track circuit sections; a recording device; a normally open circuit including a source of electro-motive force, the recording device, 65 and a movable member of each translating device; a movable member of one translating device included in the circuit of the other translating device.

9. A recording device adapted to be elec- 70 trically actuated; a first normally closed track circuit section; a second abutting normally closed track circuit section; a translating device, including movable circuit controllers, controlled by the first section; 75 a translating device, including movable circuit controllers, controlled by the first section and by the second section; a normally open circuit including a source of electro-motive force, the recording device and a 80 movable circuit controller of each translating device.

10. A recording device adapted to be electrically actuated; a normally open circuit including a source of electro-motive 85 force and the recording device; a plurality of track circuit sections; a translating device including a movable member adapted for movement in two directions controlled by each track circuit, said movable mem- 90 bers constituting the circuit controllers for closing the said normally open circuit, one of the movable members being arranged to complete the circuit only during a movement in one direction.
